Fig. E

Diagram illustrating the circuit for Fig. E. The circuit is powered by two voltage sources, E_1 and E_2 . It consists of two parallel branches. The left branch contains resistors R_1, R_2, R_3 and capacitors C_1, C_2, C_3 . The right branch contains resistors R_4, R_5, R_6 and capacitors C_4, C_5, C_6 . The circuit includes two operational amplifiers, A_1 and A_2 , with feedback paths involving transistors T_1, T_2, T_3, T_4 . The output of A_1 is connected to the non-inverting input of A_2 . The circuit is labeled with component numbers 23, 24, and 25.

RAILWAY TRAFFIC CONTROLLING APPARATUS

Application filed September 25, 1929. Serial No. 395,015.

The present invention relates in general to railway traffic controlling apparatus, but is particularly concerned with the provision of trackway equipment for controlling wayside signals in accordance with traffic conditions, and for controlling cab signal and train control equipment in accordance with traffic conditions in advance of the moving vehicles.

10 An outstanding feature of the invention has to do with the provision of trackway equipment for transmitting advance indications to a vehicle, of the condition of the wayside signal at the entrance of the block 15 which is being approached as the vehicle progresses along the trackway.

The invention is disclosed in two sheets of drawings comprising Figs. 1, 2, and 2A, which diagrammatically illustrate sufficient 20 vehicle equipment and trackway apparatus embodying the invention to enable the same to be readily understood.

Referring more specifically to the drawings, Fig. 1 shows vehicle equipment of a 25 train control system, such as that disclosed in the co-pending Hudd application, Serial No. 377,418, filed July 11, 1929. This equipment includes a magnetic-pick-up relay PR, suspended from a locomotive tender in such position that, as the tender passes over the trackway, the relay will pass through the magnetic fields of permanent and electro-magnet trackway elements, placed along the trackway, which will cause the relay to actuate 30 its armatures 107¹ to 107⁴ by magnetism picked up by magnetic flux collector plates secured to the associated pole-pieces 105¹ to 105⁴, respectively. The armatures 107¹ to 107⁴ are held into association with either of 35 their associated pole-pieces by magnetism of north polarity induced in their free ends by small permanent magnets 103. It may be mentioned, however, that these magnets are very weak compared with those placed along 40 the trackway, and therefore, the trackway magnets readily overcome the control normally exerted on the armatures by the magnets 103. Associated with the armatures 107³ and 107⁴ are a pair of armature restoring coils 108, which when energized, are ef-

fective to move the armatures 107³ and 107⁴ into association with pole-pieces 105⁶ in case these armatures are associated with pole-pieces 105³ and 105⁴ when the windings of 108 are energized.

55 An electro-pneumatic valve EPV and an associated whistle W are provided to sound a warning and to initiate an automatic brake application upon de-energization of the electro-pneumatic valve in any desired manner, for example, in the manner described in the copending application referred to.

The lamp signals G, Y, and R under the joint control of the pick-up relay PR and of an auxiliary relay 110 serve to visually 60 indicate the traffic conditions "clear", "caution", and "stop", respectively.

The vehicle equipment is shown in the position which it assumes after passing a signal at "clear". Under these circumstances the 70 relay 110, electro-pneumatic valve EPV and "clear" indicating lamp G are all energized. The circuit of the electro-pneumatic valve EPV extends from the positive terminal of the vehicle battery VB, through the break 75 contacts of the push-button PB, conductor 112, through the contacts and armatures 107⁴ and 107³ in series, over conductor 96 and through the winding of EPV back to the negative terminal of battery, supplied to the 80 common conductor 97.

The circuit for relay 110 and the lamp G extends from the positive side of the vehicle battery on conductor 112, through the contacts and armature 107¹, conductor 113, 85 armature 107² and its lower contact, to conductor 95, where the circuit divides, one branch extending through the lower winding of relay 110 to conductor 97 and the negative terminal of the battery, while the other branch extends through "clear" lamp G to conductor 97 and the negative terminal of the battery.

The trackway magnets P¹, P², and P³ are 90 simply groups of permanent magnets enclosed in an appropriate assembly, such for example, as that disclosed in the co-pending application referred to, and are arranged to influence armatures of the pick-up relay PR 100

by inducing magnetic flux in certain flux collector plates and pole-pieces thereof.

The trackway electromagnets E^1 to E^3 may be of the general type of those disclosed in the copending application referred to, and simply consist of a core having a pole-piece at each end thereof and a third pole-piece between the two windings. These electromagnets, when energized by current flow in one direction, generate magnetism of north polarity at their outer pole-pieces, and of south polarity at their middle pole-pieces, and when energized in the reverse direction generate magnetism of south polarity at their outer pole-pieces and magnetism of north polarity at their middle pole-pieces. These magnets actuate the pick-up relay PR of the vehicle by inducing magnetism into all of the pole-pieces 105¹ to 105⁶.

26 The trackway equipment shown in Figs. 2 and 2A comprises the circuits and apparatus of one block C-D with the signal control circuits and apparatus for controlling track-circuits in the rear of signal position S' omitted, as such apparatus would merely duplicate that shown at the entrance of block D-E. For similar reasons only sufficient apparatus is shown at the block in advance of D-E as is necessary to enable a complete showing of the circuits and apparatus at the entrance of block D-E to be made. In order to void unnecessarily complicating the disclosure no trackway magnet equipment has been shown at the left of the entrance to block C-D nor in any location in the block D-E.

40 The block extending from C-D is divided into three insulated track-sections, while the block D-E is divided into two insulated track-sections. The number of track-sections in a block as well as the number of advance signal indicating positions are determined by roadway and traffic requirements. Each track-section is provided with a track relay connected across the rails at the entrance end of the section. These track relays are designated T with an appropriate exponent. A suitable source of battery such as the track battery 4 extends across the other end of each 45 track section in series with a resistor 3, and if an advance indication is provided, also with an approach relay. The approach relays are designated A with a suitable exponent. At each signalling position a line relay is also provided. Two such relays L⁴ and L⁶ are shown. Also at each signal location a signal controlling relay such as C⁴ is provided. A pole-changing relay PC is also provided at each signal location and functions to control the direction of current supply to the electromagnet trackway elements E¹ to E³ in a manner which will subsequently be made clear. Other block sections obviously are equipped in a similar manner.

60 65 The trackway apparatus is shown in the

position it assumes when at least two blocks in advance of D-E are unoccupied. Under "clear" traffic conditions the track relays are all energized, but the associated approach relays are de-energized owing to the comparatively high resistance of the track relays. The line relay L⁴ is energized over a series circuit including the signal control relay C⁴. This circuit extends from the positive terminal of battery LB⁴, conductor 11, armature 13, and contact of track relay T⁴ through the winding of L⁴, line conductor 23, signal control relay C⁴, the contact and armature of track relay T⁴ over the common conductor 25 and conductor 12 to the negative terminal of the battery LB⁴. A similar circuit exists for signal control relay C⁶ and line relay L⁶. Each line relay functions to prevent the energization of any lamp of the associated signal when there is no vehicle in the preceding block. Each signal control relay functions to determine which of the signals G or Y will be energized when a train enters the block to the rear of the associated wayside signal, and when energized also prepares an operating circuit for the associated pole-changing relay PC.

With the circuits and apparatus as illustrated, a train entering track-section TS' of block C-D causes the track relay T⁴ to interrupt the traced circuit including relays C⁴ and L⁴ and due to the increased current flow, caused by shunting out the track relay, effects the energization of the approach relay A². The line relay L⁴, upon becoming deenergized, at its armature and contact completes a circuit from the positive terminal of battery LB⁴, over conductor 11, the armature and contact of L⁴, the armature 14 and front contact of track relay T⁴, conductor 17, to the armature and contact of signal control relay C⁴, where the circuit devices, one branch extending through the lamp G of signal S⁴ to conductors 10, 25, and 12 to the other terminal of battery LB⁴, and the other branch extending by way of the winding of the pole-changing relay PC, conductor 9, conductors 25 and 12 to the battery LB⁴. The lamp G of signal S⁴, therefore, lights-up the instant the train enters the first track-section of block C-D to display a "clear" indication. The pole-changing relay PC, upon becoming energized, owing to the energized condition of the approach relay A², completes a circuit for the electromagnet track element E¹. This circuit extends from the positive terminal of the train control battery TC, through the upper armature and upper contact of the pole-changing relay, the lower contact and armature of track relay T⁴, conductor 24, the armature and contact of approach relay A², the lower and upper windings of trackway electromagnet E¹, and over the common conductor 25, branch conductor 8, and upper con-

5 tact and lower armature of the pole-changing relay PC back to the other terminal of the train control battery. The current flow through trackway element E' with the pole-changing relay PC energized, is in the proper direction to generate magnetism of north polarity at the upper and lower pole-pieces and of south polarity at the middle pole-piece of this element.

10 When the train enters track-section TS² it causes the track relay T² to drop its armature, thereby interrupting the circuit of the approach relay A². The armature of T² at its back contact also places a shunt across 70 the rails at the exit end of track-section TS¹ as a further precaution against the track relay T¹ being again operated until after all track-sections of block C-D have been cleared by the passing train. The approach 75 relay A² in dropping its armature interrupts the traced circuit through the trackway element E'. The entrance of the train into the track-section TS² also causes the approach relay A³ to operate and complete the circuit 80 of the trackway electromagnet element E² in the same manner as was the circuit completed for E¹ when the train entered track section TS¹.

85 When the train enters track section TS³ the track relay T³ drops its armature which, like the track relay T², interrupts the circuit of the associated approach relay, and places a shunt across the tracks rails at the exit end of the track section TS². Obviously, 90 therefore, the track relays T¹ and T² do not again become energized until the train clears track-section TS³. When the train enters track-section TS³ the approach relay A⁴ at the exit end of the section also becomes energized and completes the circuit of the electromagnet track element E³ in the same manner as did the corresponding relay at the exit end of the former track section.

95 When the train enters track-section TS⁴ the track relay T⁴ becomes deenergized, at armature 13, interrupts a second point in the series circuit of control relay C¹ at the entrance of block C-D and of the line L⁴ at the exit end of this block, so that these 100 relays remain de-energized until the block C-D has been cleared by the train and at armature 14 interrupts the circuit of lamp G of signal S⁴ and of the pole-changing relay PC, and at the back contacts of this armature completes a circuit for the lamp R of the signal S⁴. This latter circuit extends from the positive terminal of battery LB⁴, over conductor 11, the armature and back 105 contact of line relay L⁴, armature 14 and its back contact, conductor 19, the lamp R, and conductors 10, 25, and 12 back to the other terminal of the battery LB⁴. The track relay T⁴ also, at its armature 15, 110 interrupts the circuit of signal control relay

115 C⁴ and line relay L⁶, and these relays accordingly become deenergized, and at its lowermost armature T⁴ opens a point in the operating circuit of the trackway elements E¹ to E³, so that another train passing over 120 the track-sections TS¹, TS², and TS³, while the block D-E is occupied will not bring about the energization of these trackway electromagnets. The signal control relay C⁴ in dropping its armature interrupts a second 125 point in the circuit of lamp G of signal S⁴ and of the pole-changing relay PC and prepares a point in the circuit of the lamp Y of signal S⁴.

130 When the train clears track-section TS³ the track relay T³ again becomes energized, which, in turn, causes the energization of track relays T² and T¹ in the order named. When the train enters track-section TS⁵ the track relay T⁵ drops its armature to interrupt 135 the current supply to the track-rails of the section TS⁴ and to place a shunt across the rails thereof. Obviously if this location of the trackway is to be equipped with means for giving an advance indication of the condition of the signal S⁶ an approach relay and trackway magnets such as those shown in the block C-D will have to be provided at this position. When the train enters 140 track-section TS⁶ the track relay T⁶ drops its armatures and in so doing brings about 145 circuit changes corresponding to those occurring when the track relay T⁴ drops its armatures.

150 When the train clears the block D-E the track relays T⁴ and T⁵ again become energized. When this occurs the track relay T⁴, at its armature 13, reestablishes the series circuit including line relay L⁴ and signal control relay C¹; at its armature 14 interrupts 155 the circuit of the lamp R of signal S⁴ and at the front contacts of this armature closes a second point in the circuit of lamp Y of signal S⁴. This latter circuit is now maintained 160 open, however, at the armature of line relay L⁴. The track relay T⁴ also at its armature 165 165 closes a point in the series circuit of signal control relay C⁴ and of line relay L⁶, so that when the train clears the next block in advance of D-E this circuit will be again re-established; and at its lower armature again 170 closes the common train control battery circuit which supplies current to the trackway electromagnets E¹ to E³. Obviously, when 175 the train clears the block in advance of D-E the signal control relay C⁴ is again energized, with the result that the multiple circuits of 180 lamp G of signal S⁴ and of the pole-changing relay PC are again prepared.

185 It will now be assumed that there is a 185 train standing in track-section TS⁶ or in some other track-section of the block immediately in advance of the D-E and that a second train enters and passes through the block C-D. Under the conditions assumed, the 190

track relay T^6 will be de-energized and, consequently, the signal control relay C^4 will have prepared a circuit for lamp Y of signal S^4 . Therefore, when a second train enters track-section TS^1 and track relay T^1 drops its armature to interrupt the traced circuit of signal control relay C^1 and of line control relay L^4 , a circuit is completed for the lamp Y of signal S^4 instead of lamp G of this signal and for the pole-changing relay. The circuit extends from the positive terminal of battery LB^4 , over conductor 11, the armature and contact of L^4 , armature 14 and its front contact, conductor 17, the armature and back contact of signal control relay C^4 , lamp Y and conductors 10, 25, and 12 to the negative terminal of the battery LB^4 . The "caution" signal S^4 is, therefore, displayed when the train enters the block $C-D$. The same circuit changes take place as the train progresses through the block as take place when the signal S^4 is at "clear", but since the pole-changing relay PC is de-energized under the "caution" traffic condition, the current flow through the trackway electromagnets E^1 to E^3 as each of these are encountered will be in reverse direction to that formerly and, consequently, when these electromagnet trackway elements are energized they will, under these circumstances, generate magnetism of south polarity at their outer pole-pieces, and of north polarity at their middle pole-pieces. When the train clears the block $C-D$ the signal apparatus and circuits of that block function in the same manner as formerly described.

It will now be assumed that a train enters the block $C-D$ and passes there-through, while a train is standing in one of the track-sections of block $D-E$. When a train is standing in either of these track-sections the track relay T^4 is, of course, de-energized, and, accordingly, has at its armature 14 completed the circuit of the lamp R of signal S^4 ; and at its lower armature has interrupted the train control battery feed supply for the electromagnet trackway elements of block $C-D$. Therefore, when the train enters and passes through the various track-sections of block $C-D$ and the associated approach relays become energized no circuits are completed for the trackway electromagnets of these track-sections.

From the foregoing circuit description it will be obvious that when a train approaches and passes through the block $C-D$ under "clear" traffic conditions, such conditions existing when block $D-E$ and the block in advance of $D-E$ are both unoccupied, the electromagnet trackway elements E^1 , E^2 , and E^3 are successively energized by current flow in one direction; when a train passes through the various sections of block $C-D$ with the signal S^4 displaying a "caution" indication, indicating that the blocks $C-D$ and $D-E$, are

unoccupied but that the block in advance of $D-E$ is occupied, the current flow through the electromagnet track elements E^1 , E^2 , and E^3 will be in the reverse direction; and that when a track-section of block $D-E$ is occupied and a train passes through the various sections of block $C-D$ no current will flow through the trackway electromagnets E^1 , E^2 , or E^3 .

With the foregoing facts in mind consideration will now be given to the effects produced in the vehicle equipment as a train passes over the various sections of block $C-D$ under "clear," "caution," and "stop" condition of the signal S^4 , respectively.

As the pick-up relay PR passes over the permanent magnet track element P^1 magnetism of south polarity is induced in the pole-pieces 105^1 and 105^3 , or in the pole-pieces 105^2 and 105^4 , depending upon the polarity of the permanent magnet P^1 . The operation of either pair of armatures 107^2 and 107^4 or 107^1 and 107^3 brings about the same circuit changes, and it will, therefore, be assumed that the magnet P^1 as well as the other permanent magnet trackway element shown are of the proper polarity to cause armatures 107^1 and 107^3 to be operated into engagement with their pole-pieces 105^1 and 105^3 , respectively. The armature 107^3 , in operating interrupts the traced circuit through the electro-pneumatic valve EPV , thereby causing the same to become deenergized and initiate a brake application, and at the same time causes the whistle W to sound. The armature 107^1 in-

terrupts the circuit passing through the lower winding of relay 110 , and the "clear" indicating lamp G in multiple and, accordingly, the lamp G is extinguished, and the relay 110 de-energized. The "stop" indicating lamp R does not light-up, however, as its circuit is now opened at the armature 107^3 . The trackway electromagnet E^1 is located a distance in advance of P^1 which requires less than a six-second period of time for the train to travel the distance between them unless the vehicle is traveling at a very low speed so that it is passed over before a brake application can actually occur. When the trackway electromagnet E^1 is encountered by the pick-up relay, since the outer pole-pieces of the electromagnet are of north polarity and the middle pole-pieces thereof is of south polarity, this magnet will be effective to restore the armatures 107^1 and 107^3 , because the trackway electromagnet E^1 induces magnetism of north polarity in the pole-pieces 105^1 and 105^3 and, therefore, repels the armatures 107^1 and 107^3 . It also induces magnetism of north polarity in the pole-pieces 105^2 and 105^4 , so that should these armatures have been operated they would have also been restored at this time. The armatures 107^1 and 107^3 , upon becoming restored, simply restore the condition of vehicle equipment existing prior to

the encountering of trackway element P^1 . The momentary sounding of the whistle, however, and the re-lighting of the lamp G in the cab of the vehicle serves to inform the engine-man that the signal at the entrance to block D-E is displaying a "clear" indication, and that the train may proceed at full speed. The trackway elements P^2 and E^2 control the vehicle equipment in the same manner as did the elements P^1 and E^1 . Likewise, at the exit end of the track section TS^3 the same operations of the vehicle equipment occur.

It will now be assumed that a train enters block C-D with the signal S^1 displaying a "clear" indication, but that there is also a train standing in track-section TS^6 or some other track-section of that block. Under these circumstances it will be recalled that no circuit exists for the pole-changing relay PC at signal position S^4 ; consequently, the train passing through block C-D successively energizes electro-magnet trackway elements E^1 , E^2 , and E^3 in the proper direction to cause them to generate magnetism of south polarity at their outer pole-pieces and magnetism of north polarity at their middle pole-pieces. The pick-up relay UR in passing over the permanent magnet trackway element P^1 , as before, initiates an automatic brake application and extinguishes the green lamp G formerly displaying a "clear" indication in the cab. A few seconds later, however, the pick-up relay passes over the electromagnet trackway element E^1 . When this occurs since the electromagnet trackway element now generates magnetism of south polarity in its outer pole-pieces, it induces magnetism of south polarity in the pole-pieces 105¹ to 105⁴, inclusive, and since its middle pole-piece is of north polarity it induces magnetism of north polarity in the inner pole-pieces 105⁵ and 105⁶ which assist the attractive effect produced in the pole-pieces 105¹ to 105⁴ by tending to repel the armatures. The armatures 107² and 107⁴, therefore, also move into engagement with their outer pole-pieces. Armature 107⁴, in operating, merely breaks a second point in the traced circuit for the electro-pneumatic valve EPV, while the armature 107², in addition to breaking a second point in the traced circuit for the "clear" indicating signal G and lower winding of relay 110, establishes a circuit for the "caution" signal Y and upper winding of relay 110. This circuit extends from the positive terminal of the vehicle battery VB, through the break contact of the push-button PB, conductor 112, the upper contact and armature 107², conductor 113, the armature 107¹ and its lower contact, conductor 114, and the upper winding of relay 110 and "caution" signal Y in multiple to the negative terminal of the battery VB. Accordingly, relay 110 is immediately energized to maintain the circuit of the "stop" signal

R open and the "caution" signal Y is lighted to inform the engine-men that the way-side signal S^4 at the entrance to the next block in advance is displaying a "caution" indication, and that they should proceed with caution until a more favorable signal is received in the cab. The display of the "caution" signal in the cab instead of the "clear" signal also advises the enginemen that acknowledgement of the restrictive indication must be made at once to avoid an automatic brake application by momentarily operating the push-button PB. The pressing of this button interrupts, at its back contact, the circuit of the lamp Y and relay 110 while this push-button at its front contact completes a circuit through the armature restoring windings 108, causing the armatures 107³ and 107⁴ to be restored to their normal position in which they are shown. The restoration of these armatures simply causes the previously traced circuit through the electro-pneumatic valve EPV to be re-established, and serves to prevent an automatic brake application occurring in the manner described, for example, in the co-pending application referred to.

If the train remains standing in the block in advance of D-E the same circuit changes will be brought about in the vehicle as it passes over the trackway elements at the exit ends of track-sections TS^2 and TS^3 , respectively. It will be assumed, however, that the train in the block immediately in advance of D-E clears such block prior to the time that the pick-up relay in the following vehicle passes over the trackway elements P^2 and E^2 . Under these circumstances the signal control relay C^4 will be energized as will also the pole-changing relay PC. Consequently when the pick-up relay PR passes over the electromagnet trackway element E^2 , instead of causing the "caution" lamp Y to be displayed in the vehicle cab, will restore the operated armatures to the position shown, causing the electro-pneumatic valve EPV to be again energized and the "clear" signal G to be again displayed. The signal change in the cab informs the engine-man that the block signal in advance has changed from a "caution" to a "clear" indication, and that the train may proceed at full speed.

If the train in advance of block D-E for some reason backs into block D-E after the following train receives the "caution" indication in the cab as a result of having passed trackway element E^1 , the trackway relay T⁴ will be de-energized with the result that no current will be supplied to the trackway device E^2 when the pick-up relay passes thereover. Under such circumstances when the train passes over the permanent magnet P^2 and a brake application is initiated the electro-pneumatic valve EPV remains de-energized and the "caution" signal remains

extinguished. Under these circumstances an engine-man must acknowledge as he did in passing the trackway magnet E^1 , to re-establish the circuit for the electro-pneumatic valve EPV. This time, however, since the electromagnet E^2 does not transmit any influence to the pick-up relay the armatures 107¹ and 107² will be in the position they were moved by the permanent magnet P^2 —i. e. 10 armatures 107¹ and 107² will be in engagement with their respective lower contacts. Consequently no circuit exists for the relay 110 or 15 for the signal Y, but instead "stop" signal lamp R is bridged in multiple with the winding of the electro-pneumatic valve EPV, and, accordingly, lights up to display a "stop" indication in the cab. The display of the "stop" indication at this time informs the engine-men that they must proceed with extreme caution because the block in advance 20 is occupied.

What is claimed is:

1. In a train control system, a vehicle equipped with a device responsive to impulses transmitted from the trackway, a stretch of trackway divided into a plurality of block sections; a block section in said stretch equipped with trackway means for periodically inductively transmitting brake initiating impulses to said device, irrespective of traffic conditions in advance of said block; and a single electromagnetic traffic controlled trackway element encountered, subsequent to the initiation of each brake application 30 impulse to variably modify the condition of said device in accordance with traffic conditions in the blocks in advance.
2. In a train control system, a stretch of track divided into a plurality of block sections, and traffic controlled trackway electromagnets distributed along certain of said block sections for each transmitting an impulse to a vehicle passing thereover to produce signal indications in said vehicle in accordance with the traffic conditions of a plurality of said block sections in advance, said electromagnets each having a single core equipped with three pole pieces.
3. In a train control system, a stretch of track divided into block sections, a block in said stretch further divided into a plurality of insulated sections, a track relay connected across the rails at the entrance of each section, an approach relay and battery connected in series across the rails at the exit end of each section for causing the energization of said track relays while their respective sections are clear and operative by an increase of current flow caused by such section being occupied; a permanent magnet and an electromagnet trackway element placed along the trackway, in the order named, at the exit of each section for transmitting train control impulses to passing vehicles; circuits for said electromagnet elements, and means including

the respective approach relays for completing the circuits of said electromagnet elements successively as a vehicle passes through said block when the next block in advance is unoccupied.

4. In a train control system, a stretch of track divided into block sections, a block in said stretch further divided into a plurality of insulated sections, a track relay connected across the rails at the entrance of each section, an approach relay and battery connected in series across the rails at the exit end of each section for causing the energization of said track relays while their respective sections are clear and operative by an increase of current flow caused by such section being occupied; a permanent magnet and an electromagnet trackway element placed along the trackway, in the order named, at the exit of each section for transmitting train control impulses to passing vehicles; circuits for said electromagnet elements, and means including the respective approach relays for completing the circuits of said electromagnet elements successively as a vehicle passes through said block when the next block in advance is unoccupied.

5. In a train control system, a stretch of track divided into block sections, a block in said stretch further divided into a plurality of insulated sections, a track relay connected across the rails at the entrance of each section, an approach relay and battery connected in series across the rails at the exit end of each section for causing the energization of said track relays while their respective sections are clear and operative by an increase of current flow caused by such section being occupied; a permanent magnet and an electromagnet trackway element placed along the trackway, in the order named, at the exit of each section for transmitting train control impulses to passing vehicles; circuits for said electromagnet elements, means including the respective approach relays for completing the circuits of said electromagnet elements successively as a vehicle passes through said block, and means depending upon the occupied or un-occupied condition of the second block in advance determining the direction of current flow through said circuits.

6. In a train control system, a block divided into a plurality of insulated track sections, an electromagnet track element at the exit end of each section, means for energizing one of said electromagnets when a vehicle enters the section in which it is located, means for simultaneously causing the de-energization of said electromagnet and for energizing the electromagnet at the exit end of the section in advance as the vehicle enters the latter section, and traffic controlled means for determining the direction of current flow through said magnets.

7. In a train control system, a stretch of

trackway divided into block sections, wayside signals at the entrance to each section for displaying clear, caution, and stop indications, respectively, a vehicle on said trackway also provided with clear, caution, and stop signals, magnetic induction trackway means for causing said cab signals to display signal indications corresponding to the indications displayed by the wayside signals at the time the block is entered providing such signals are at clear or caution and for wiping out any prior operated cab signal if the wayside signal is at stop, other magnetic inductive trackway means effective as the vehicle passes through such block to cause the vehicle signals to periodically repeat the signal displayed at the entrance of the next block in advance if and only if such signal is at clear or caution, and manually controlled means on the vehicle operative subsequent to the wiping out of any prior operated signal subsequent to passing a wayside signal at stop for preventing an automatic brake application and for causing the cab signal to indicate stop.

8. In a trackway system divided into block sections, each provided with wayside signalling equipment, trackway equipment at the exit of a block, for wiping out any existing cab signal and for then reproducing in the vehicle passing thereover, a signal indication corresponding to that of the wayside signal at the entrance to the next block in case such wayside signal is at clear or caution, other trackway means to the rear of the first mentioned trackway means for also wiping out any existing cab signal and for then reproducing an advance indication in the vehicle of the condition of the signal at the entrance to the next block only in case it is displaying a clear or caution indication, and manually controlled means operable after passing a signal at stop for preventing an automatic brake application and causing the display of a stop signal in the vehicle.

9. In combination with a stretch of trackway divided into a plurality of block sections, wayside signalling apparatus at the entrance to each block for displaying clear, caution, and danger traffic conditions, respectively, trackway means at exit end of the preceding block for causing said wayside signal indications to be reproduced in the cab of a vehicle entering a block only when such signal indicates clear or caution, other trackway means in said preceding block for causing the signal indications of the block in advance of it to be periodically reproduced in the vehicle as it passes through the preceding block only when such signal indicates clear or caution, and vehicle carried means controlled manually to cause the display of a stop indication thereon subsequent to passing a wayside signal at stop.

10. In a train control system, a stretch of

track divided into block sections, a block in said stretch further divided into a plurality of insulated sections, a track relay connected across the rails at the entrance of each section, circuits for causing the energization of said track relays while their respective sections are clear, a permanent magnet and an electromagnet trackway element placed along the trackway, in the order named, at the exit of each section for transmitting train control impulses to passing vehicles, and circuits for said electromagnet elements under control of said track relays and completed successively as a vehicle passes through said block when the next block in advance is unoccupied.

11. In a train control system, a stretch of track divided into block sections, a block in said stretch further divided into a plurality of insulated sections, a track relay connected across the rails at the entrance of each section, circuits for causing the energization of said track relays while their respective sections are clear, a permanent magnet and an electromagnet trackway element placed along the trackway, in the order named, at the exit of each section for transmitting train control impulses to passing vehicles, circuits for said electromagnet elements under control of said track relays and completed successively as a vehicle passes through said block when the next block in advance is unoccupied, and traffic controlled means for determining the direction of current flow through said electromagnet elements.

In witness whereof, I hereunto subscribe my name this 18th day of September, A. D. 1929.

ALFRED E. HUDD.
